UNITED STATES PATENT OFFICE.

THOMAS J. KANIFF, OF CHICAGO, ILLINOIS.

DESIGN FOR A CIGARETTE-PAPER CASE.

53,367.

Specification for Design.

Patented May 27, 1919.

Application filed September 12, 1918. Serial No. 253,837. Term of patent 14 years.

To all whom it may concern:

Be it known that I, THOMAS J. KANIFF, a citizen of the United States, residing at Chicago, in the county of Cook and State of Illinois, have invented a new, original, and ornamental Design for Cigarette-Paper Cases, of which the following is a specification, reference being had to the accompanying drawing, in which a perspective view of the design is shown.

I claim:

The ornamental design for a cigarette paper case, as shown.

In testimony whereof I affix my signature.

THOMAS J. KANIFF.
